FIG. 2

FIG. 3

INVENTOR
JOSEPH D. BELL

or F. M. Wright

ATTY.

UNITED STATES PATENT OFFICE.

JOSEPH D. BELL, OF ROCKFORD, ILLINOIS.

DAVENPORT-BED.

1,366,112.

Specification of Letters Patent. Patented Jan. 18, 1921.

Application filed April 15, 1918. Serial No. 228,718.

To all whom it may concern:

Be it known that I, JOSEPH D. BELL, a citizen of the United States, residing at Rockford, in the county of Winnebago and State of Illinois, have invented new and useful Improvements in Davenport-Beds, of which the following is a specification.

The object of the present invention is to provide a simple and easily operated davenport bed so constructed as to support and conceal, when used as a davenport, a mattress of the greatest thickness used on an ordinary bed.

In the accompanying drawing, Figure 1 is a vertical longitudinal section showing the device extended for use as a bed, showing also in dotted lines the position of certain of its parts when partly folded for use as a davenport; Fig. 2 is a similar view of the device, showing the position of certain of its parts when partly folded for use as a davenport; Fig. 3 is a similar view showing when wholly folded for such use.

Referring to the drawing, 1 indicates one of the two ends of the davenport frame mounted upon rollers 2 and having secured thereto a base board 3. Although only one side of the bed and one end of the davenport are here shown, it is to be understood that both sides and ends are alike. Hinged, as shown at 4, to the top of said base board is a front board 6 of a seat frame 7, having sides 8 extended behind the seat 9, and carrying legs 11 mounted upon rollers 12, upon which the free end of the seat is supported when in its extended position. To the sides 8 of the seat frame are pivoted, as shown at 13, ends of links 14, the other ends of which are pivoted, as shown at 16, to the rear ends of the sides 17 of a short terminal mattress frame section 18, which constitutes the foot portion of the mattress frame, and also to the sides 19 of an intermediate mattress frame section. The other ends of said sides 19 are pivoted, as shown at 21, to ends of sides 22 of the other terminal mattress frame section 23, the other ends of which sides carry on their outer sides pins 24.

Said pins 24 slide in grooves 26 in plates 27 secured on the inner surfaces of the davenport ends, said grooves extending for the most part in a vertical direction, but having short lower portions 28 extending horizontally forward. The sides 22 of the terminal mattress frame section 23 are piv-

otally attached, as shown at 29, to the upper ends of links 31, the lower ends of which are pivotally attached, as shown at 32, to plates 33 secured to the davenport ends near their lower edges.

The front terminal section 18 is held in either a horizontal or a vertical position. It is held in the latter position by means of bars 34 each pivotally attached at one end to said terminal section 18 and at the other end provided with means for detachably securing it to the sides 19 of the intermediate mattress frame section. Said means may be either an ordinary hook formed in the bars 34 engaging a pin or any other suitable means, this construction constituting no part of my present invention.

In moving the device from its position for use as a bed, as shown in Fig. 1, to its position for use as a davenport, as shown in Fig. 3, first the short terminal section 18 of the mattress frame is moved into a position shown in dotted lines in Fig. 1 at right angles to the intermediate section, and suitably secured in such position automatically, or otherwise, and then the intermediate and short terminal sections are swung rearwardly about the pivots 16 as an axis. This motion of the intermediate section transmitted to the terminal section 23 causes the pins 24 of said section, which were in the short horizontally extending portions 28 of the grooves 26, to move rearwardly. Up to that time the pivots 21 of said intermediate and long terminal sections could not be depressed by the weight of a person upon the bed, for the reason that such depression could only take place simultaneously with the rise of the other end of said terminal section 23, since the middle portion of the latter section is supported upon the links 31 and the pins 24 were engaged in the horizontal portions 28 of the grooves. But when the intermediate section is swung rearwardly, this causes the pins 24 to move rearwardly, out of the horizontally extending portions 28 of the grooves, and into the vertically extending main portions of the grooves in which said pins can ascend.

Thereupon the front ends of the side pieces of the terminal section 23 descend, carrying with them the rear ends of the side pieces 19 of the intermediate section, so that the mattress frame finally assumes the position shown in Fig. 2, in which the links 14 rest upon the bottom

of the front board 6 of the seat frame, which bottom is then uppermost. The next operation is to swing the seat frame into the position shown in Fig. 3, and it will be apparent that, when so swinging said seat frame, the terminal section 18 and the front end of the intermediate section will descend and be entirely concealed within the davenport frame. The reverse operation is performed in opening out the device for use as a bed. When in this position it will be observed that the terminal mattress frame section rests upon the legs 11.

The wire mattress 35 is attached at its ends to the outer ends of the terminal mattress frame sections.

If desired, springs may be placed on the links 31, to reduce the labor of the operator in opening or closing the bed.

The manner in which the back 36 of the davenport, shown in dotted lines in Fig. 3, is raised and lowered, forms no part of any invention, as it may be done by any suitable or preferred means, and is therefore not herein described and illustrated.

As the seat is inverted, the front board 6 of the seat frame and the base-board 3 form, one or the other, a stop for arresting the downward movement of the adjacent portions of the links 14, and, therefore, form fulcrums for said links, which then act as levers, to which the power is applied at 13 by the descent of the seat frame 7 to raise the pivot 16 to a level above the top of the base-board 3, thus employing the weight of the seat itself, when inverted, to raise the front portion of the mattress frame, and facilitate the extension of these parts, as shown in Fig. 1.

I claim:

1. The combination of a davenport frame having a back, and a seat hinged to the front of the frame and movable on its hinge to an inverted position in front of the frame, a bed bottom including pivotally connected sections, the rear section occupying an upright position at the back of the frame and another section occupying a substantially horizontal position within the bottom of the frame in the folded condition of the bed bottom, a link disposed below the bed bottom in its operative position and pivoted to the davenport frame and to the rear bed section intermediate the ends thereof, the pivotal connection between the link and the bed section constituting a swinging fulcrum

on which the bed section turns in moving from its operative position to its folded position, and another link disposed below the bed bottom in its operative position and pivotally connected to the seat and to said other bed section, and means for guiding the rear end of the rear bed section in an upward direction from its operative position to its folded position.

2. In a davenport bed, the combination of a davenport frame having a back, and a seat hinged to the front of the frame and movable on its hinge to an inverted position in front of the frame, a bed bottom including pivotally connected sections, the rear section occupying an upright position at the back of the frame and another section occupying a substantially horizontal position within the bottom of the frame in the folded condition of the bed bottom, a link disposed below the bed bottom in its operative position and pivoted to the davenport frame and to the rear bed section intermediate the ends thereof, the pivotal connection between the link and the bed section constituting a swinging fulcrum on which the bed section turns in moving from its operative position to its folded position, another link disposed below the bed bottom in its operative position and pivotally connected to the seat and to said other bed section, and means for guiding the rear end of the rear bed section in an upward direction from its operative position to its folded position, said guiding means including a pair of upright guides having corresponding offsets at the lower ends, and devices carried by the rear bed section and working upon the respective guides, the offset portions of the guides overhanging said devices in the operative position of the bed bottom.

3. In combination with a davenport bed having a forwardly invertible seat frame pivotally supported on the davenport bed frame, links, each pivotally connected at one end to the davenport seat frame, an extensible mattress frame pivotally connected to the other ends of said links, one of said elements, the davenport bed frame or seat frame having a part adjacent to the pivot of the seat frame to the bed frame engaging said links to form a fulcrum, converting said links into levers for raising the mattress frame by the descent of the seat frame in inverting the latter.

JOSEPH D. BELL.
